UNITED STATES PATENT OFFICE.

ALEXANDER FISCHER AND ALBERT T. OTTO, OF NEW YORK, N. Y.

SPEED-CHANGING MECHANISM.

SPECIFICATION forming part of Letters Patent No. 661,967, dated November 20, 1900.

Application filed June 24, 1897. Renewed April 22, 1899. Serial No. 714,133. (No model.)

To all whom it may concern:

Be it known that we, ALEXANDER FISCHER and ALBERT T. OTTO, citizens of the United States, and residents of the city, county, and 5 State of New York, have invented certain new and useful Improvements in Speed-Changing Mechanism, of which the following is a specification.

Our invention relates to speed-changing mechanism for varying the relative rate of revolution of a driving and a driven part wherein the variation may be produced while the mechanism is in motion.

Our invention is especially applicable to road-vehicles wherein a small motor is used, being driven at a high and practically uniform speed, while the leverage of the motor on the traction-wheels must be varied to compensate for the extreme variation in natural 20 grades and for the different conditions of roads, and our invention is also applicable for the purpose of starting and stopping the vehicle without interrupting the motion of the motor.

25 The object of our invention is to reduce the number of parts and simplify the machine, thereby condensing the same into a small space, which is a desirable feature in the construction of road-motors.

30 Our invention consists in certain novel features of reciprocating clutch-actuating mechanism hereinafter described and claimed, wherein a high-speed rotary motion is converted into a low-speed rotary motion through 35 a crank-pin acting at a variable radius, which may be varied from a maximum stroke to an elimination of stroke while the machine is in motion.

Referring to the accompanying drawings, 40 Figure 1 is a side elevation, illustrating our improved mechanism. Fig. 2 is an enlarged vertical section taken at $y-y$, Fig. 1. Fig. 3 is a cross-section at $z-z$, Fig. 2. Fig. 4 is an enlarged detail side view of a clutch suitable 45 to our invention, showing the reverse side from that appearing in Fig. 1. Fig. 5 is an interior view of the same. Fig. 6 is a cross-section at $x-x$, Fig. 4.

A, Fig. 1, represents a motor, the same acting on a crank C (partly shown in Fig. 2) to

continuously revolve the rotary driving shaft or part B'. A fly-wheel F' is provided to steady the motion.

A crank-pin T is movably mounted on the fly-wheel F' and is slidingly connected directly with the clutch-lever K. The crank-pin T is adjustable in position and may be changed in adjustment while the machine is in motion by means of a movable collar U' on the shaft B', which is mechanically connected 55 to the sliding block 20 of the pin T by means of a series of steel balls 21 or other flexible chain of elements running in a loop-shaped channel 22, as illustrated in Fig. 2. For convenience a lever 23 is connected to the collar 60 U and secured in position by a screw 24, which can be screwed into the lever 23, so as to press on the circumference of the circular boss of the lever-fulcrum, as shown in Fig. 2, or may be partially withdrawn therefrom by 65 rotating the said screw 24 by means of a handle 24^a. This lever holds the crank-pin at any desired point of adjustment and so may be used to move and hold the crank-pin T at 70 different radii while the machine is in motion, 75 or any other convenient means of operating the collar U may be employed. The collar U' is provided with a narrow inward projection 25, (a separate part of which, 26, is adjustable by set-screws to take up wear of 80 the balls,) and said projection plays in the groove 27 to engage with the balls by the movement of the collar. The block 20 of the crank-pin T is also made narrow where it intersects the groove 28 to engage with 85 the balls 21, as seen in cross-section in Fig. 3, and the block terminates in a T-shaped head, whereby it is guided in a groove 29 in the body of the fly-wheel F', which is constructed in two parts, divided at the line $y-y$, 90 Fig. 1, for convenience and bolted firmly together. The slide 20 being limited in its movement by the hub 30, the pin T is offset on said slide or block by the arm 31, so that when the block is moved to its limit toward 95 the center of the shaft B' the crank-pin T shall coincide with the said center and eliminate motion of the clutch-lever K. In Fig. 2 the crank is shown at its position of maximum stroke. In Fig. 1 the crank is shown 100

at a position of medium stroke, and the dotted lines indicate the maximum-stroke position at T' and the stationary position at T^2 . The crank T may be connected to the clutch

5 L through any suitable mechanical device. We illustrate herein as a part of our invention the vibrating rock arm or lever K, having direct engagement with the crank T, which acts in the slot K', so as to vibrate said 10 lever by the continuous rotary movement of said crank. The clutch L may be constructed in any usual or suitable manner for purposes of our invention, the same being adapted to avoid lost motion. We illustrate a construction of clutch corresponding to that described in Letters Patent of the United States 15 No. 432,473. The lever K is loosely mounted on the shaft M and is connected to the plate 4 of the clutch by a slot and pin 5, and, as seen more clearly in Figs. 4, 5, and 6, the plate 20 4 bears a projection 6, which is adapted to pry the segments 7 8 apart when the plate is moved in the direction of the arrow and cause said segments to bind instantly on the flange 9, which is fixed to the shaft M. The 25 segments 7 8 are normally held together with moderate pressure and away from the flange 9 by means of the spring 10. This causes the clutch to release during recovering movement, but avoids the necessity of any considerable lost motion between the parts, which 30 would have to be taken up when the propelling movement commences, as more fully described in said patent. An important advantage 35 of the direct connection of the crank T to the arm K consists in that during the propelling motion of the clutch L the crank-pin T may act on a long radius of the arm or lever K, giving great power, while during the 40 recovering stroke of said clutch the crank-pin T may act on a short radius of said arm, thereby recovering the clutch with a quick motion preparatory to a successive stroke.

Our invention has the advantage that the 45 motor may be continuously operated, while the mechanism driven thereby may be started or stopped or changed in speed instantly and without the loss of time incurred in starting and stopping the motor, especially when explosive gas is used as the motive power. The 50 invention is especially useful in hill-climbing when used on road-vehicles, it being desirable that the working capacity of the motor be immediately convertible from speed 55 advantage into power advantage, and vice versa.

Having thus fully described our invention, what we claim, and desire to secure by Letters Patent, is—

60 1. In a speed-changing mechanism, the combination of a rotary driving part, a crank thereon, a clutch engaging in one direction and releasing in the other and having a rock-arm, said arm being operated by a sliding 65 contact of said crank thereon at long radii

when effecting the engaging movement of said clutch and at short radii when effecting the recovering movement of the said clutch, a rotary driven part engaged by said clutch, and means for varying the stroke of said crank 70 while the machine is in motion.

2. The combination of a rotary shaft, a crank-pin movably mounted thereon, and means for controlling the position of said crank-pin while the shaft is in motion, consisting in guiding means for said pin, a ball-channel containing a series of balls acting on said pin, said channel extending to and longitudinally within the shaft, and a controlling member movable in the length of the shaft 80 having contact with the balls in said channel.

3. The combination of a rotary shaft, a crank-pin movably mounted thereon, and means for controlling the position of said crank-pin while the shaft is in motion, comprising guideways for the pin, a loop-shaped channel parallel to said guideways throughout a portion of its length, and extending out longitudinally of the shaft through another portion of its length, and a flexible chain of 90 elements extending through said loop-shaped channel and connected to the crank-pin.

4. The combination of a rotary shaft, a crank-pin movably mounted thereon, and means for controlling the position of said 95 crank-pin while the shaft is in motion, comprising guideways for the pin, a loop-shaped channel parallel to said guideways throughout a portion of its length, and extending out longitudinally of the shaft through another 100 portion of its length, and a flexible chain of elements extending through said loop-shaped channel, and connected to the crank-pin, together with the sleeve longitudinally slidable on the shaft and connected to said flexible 105 chain of elements.

5. The combination of a rotary shaft, a crank-pin movably mounted thereon, and means for controlling the position of said 110 crank-pin while the shaft is in motion, comprising guideways for the pin, a loop-shaped channel parallel to said guideways throughout a portion of its length, and extending out longitudinally of the shaft through another portion of its length, and a flexible chain of 115 elements extending through said loop-shaped channel and connected to the crank-pin, together with the sleeve longitudinally slidable on the shaft and connected to said flexible chain of elements, and means carried by said sleeve for taking up slack in the flexible chain 120 of elements.

6. The combination of a rotary shaft, a crank-pin movably mounted thereon, and means for controlling the position of said 125 crank-pin while the shaft is in motion, comprising guideways for the pin, a loop-shaped channel parallel to said guideways throughout a portion of its length, and extending out longitudinally of the shaft through another 130

portion of its length, and a flexible chain of elements extending through said loop-shaped channel and connected to the crank-pin, together with the sleeve longitudinally slidable on the shaft and connected to said flexible chain of elements, and an adjusting-lever connected to said sleeve.

Signed in the city, county, and State of New York this 23d day of June, A. D. 1897.

ALEXANDER FISCHER.
